FIG. 1 is a perspective view of an Elizabethan pet collar, illustrated in an assembled configuration, showing our new design;

FIG. 2 is a front elevational view thereof, illustrated in a flat configuration;

FIG. 3 is a rear elevational view thereof, illustrated in the flat configuration;

FIG. 4 is a left-side elevational view thereof, illustrated in the flat configuration;

FIG. 5 is a right-side elevational view thereof, illustrated in the flat configuration;

FIG. 6 is a top plan view thereof, illustrated in the flat configuration;

FIG. 7 is a bottom plan view thereof, illustrated in the flat configuration; and,

FIG. 8 is a front elevational view thereof, illustrated in the assembled configuration.

The broken lines showing a dog in FIG. 1 are included for the purpose of illustrating the invention in use, and form no part of the claimed design.
